ACCESSORY FOR SWITCHES

William H. Frank, Detroit, Mich., assignor to
 Bulldog Electric Products Company, Detroit,
 Mich., a corporation of West Virginia

Application October 29, 1934, Serial No. 750,560

10 Claims. (CL 200—34)

This invention relates to wall switches, and particularly aims to provide an accessory to be utilized in connection with conventional wall switches to give time delay operation to the switch; and this application continues the prosecution of application Serial No. 667,643, filed April 24, 1933.

Objects of the invention will presently appear upon reference to the following detailed description of several embodiments of the same which are disclosed in the appended drawings.

In these drawings—

Fig. 1 is a cutaway side view of a conventional tumbler switch and its associated parts, and a time delay mechanism mounted in accordance with the spirit of the invention, parts being shown in section.

Fig. 2 is an enlarged sectional view on line 2—2 of Fig. 1 showing parts of the time delay mechanism.

Fig. 3 is a front view of the disclosure of Fig. 1, the time delay mechanism being shown in operative position, in full lines, and swung to inoperative position with respect to the switch operator, in dotted lines.

Figs. 4, 5 and 6 show three alternative constructions providing different methods of mounting the time delay mechanism, Fig. 6 showing the mounting as used for a plate thru which projects three switch operators, with any one of which the mechanism may be used.

Fig. 7 shows a time delay mechanism mounted for use with a push button switch.

Fig. 8 is a front view of the disclosure of Fig. 7. Fig. 9 is a front view of a time delay mechanism mounted for use with the switch operator of a rotary switch.

Fig. 10 is a side view, like Fig. 1, but showing a modified construction, having means providing universal adjustment of the mechanism with respect to the switch operator.

Figs. 11—13 are detail partial sections thereof, as if on planes represented by lines 11—11, 12—12, and 13—13 of Fig. 10.

Fig. 14 is a front view, like Fig. 3, showing the parts arranged for automatic trigger operation.

Fig. 15 is a top plan view of Fig. 14.

Referring to the drawings, and more particularly to Figs. 1 and 3 it will be seen that the embodiment of these figures is disclosed in connection with a conventional tumbler wall switch. The switch is disclosed in juxtaposition to a wall provided with a recess bounded by the lines 11 and containing a conventional metal switch box 12, the wall having a finishing plaster surface

indicated at 14. The switch is disposed in the switch box 12 and includes a body 16, in front of which there is a mounting strap 18 normally secured to and generally sold and considered as part of the switch itself. Projecting upwardly from the mounting strap is the switch operator 20 which, for the tumbler switch shown, is in the nature of a lever. It is well known that the switch and its mounting strap and its operator are inserted into the box 12 as a unit and held therein by means of screws 22 threaded through the strap 18 and into flanges or ears formed from the switch box 12.

The recess 11 and all of the parts of the switch except a portion of the lever or operator 20 are generally concealed by a cover plate 24 of considerable area, the cover plate being secured with respect to the wall 10 by means of screws 26 passing thru holes 27 and threaded into the strap 18, the heads of the screws engaging the cover plate 24 and holding the latter in place. The cover plate as is well known is provided with an elongated slot 28 thru which the operator 20 projects and all that is visible from the front of the wall are the operator 20, the cover plate 24, and the heads 25 of screws 26.

That which has so far been described forms no part of our present invention, for our invention relates to an accessory to be used with a switch of the type just described or of an equivalent type. The accessory is in the nature of a time delay mechanism for giving a time delay action to the switch, the mechanism having an operating part adapted to move and engage the switch operator 20 to provide such action.

The accessory disclosed in Figs. 1 to 3 will now be described with reference to these figures. The accessory includes a mounting plate 40 secured with respect to the wall 10 by one of the screws 26, the latter passing thru a hole of mounting plate 40, the mounting plate overlying the cover plate 24, substantially as indicated, and having bevelled edges conforming to the bevelled edges of the cover plate, if desired. Bevelling the edges prevents the accessory from turning, with respect to the cover plate, even when it is held by only one screw. Riveted to the mounting plate, by means of a suitable rivet 42, is a stamping 44 which is bent to provide a back part 46 through which passes the rivet 42 and a top part 48 to 50 which is spot-welded the cylinder 50 of the time delay mechanism.

Disposed within the cylinder 50 is a piston rod 52 having a piston 54 secured thereto at an end thereof. The piston rod projects through

5 a cover 56 provided on the lower open end of the cylinder 50 and at its lower end is provided with a button 58. The piston rod 52 is hollow for a considerable distance and in the hollow thereof is disposed a coiled compression spring 60 which tends to advance the piston rod out of the cylinder when permitted. The coiled spring 60 is guided on a post 62 formed on a spider 64 loosely disposed within and adjacent the upper 10 end of the cylinder 50.

10 A screw having a head 66 and a rubber gasket 68 is threaded into the upper end of the cylinder 50 and thru the top 48 of the stamping 44 and the thread-fit for this screw permits more or 15 less air to enter the cylinder 50 thru the threaded opening, for purposes to be described, the screw providing an adjustment for the pressure seal effected by gasket 68.

20 A locking means for the piston rod 52 is provided and the same is in the nature of a sheet metal stamping 72 secured to cylinder head 56 by a rivet and slot connection 73—73a, and having a cutout 74 and a spring extension 76, the cutout 74 cooperating with a groove 77 formed 25 in the piston rod 52. The stamping 72 has an extension which projects thru aligned slots 78 of the cylinder 50 and of the flange of the bottom cover plate 56 and is provided with an upwardly bent handle portion or trigger lug 80 by 30 means of which the stamping can be flexed so that its cutout is in or out of registry with groove 77 of the piston rod.

35 The time delay mechanism as a whole may be swung out of the full line position of Fig. 3 to the dotted line position of Fig. 3, on the rivet 42 as a pivot, and a teat 82 formed on the back 46 of the stamping 44 co-operates with one or another of the snap depressions 84 formed on the engaged surface on the mounting plate 40 to, 40 locate the time delay mechanism with respect to its mounting plate and to hold the mechanism securely in place with respect to its mounting plate, regardless of the position occupied by the mechanism.

45 When the time delay mechanism is swung to its inoperative position, as in Fig. 3 (dotted lines), the switch operator 20 may be operated manually as desired with complete freedom and without interference.

50 However, when a time delay action is desired, the mechanism is swung to the full line position of Fig. 3, corresponding to the position of Fig. 1, and the time delay mechanism is then placed in operative relation with respect to operator 20. Before the time delay action is started, the parts of the mechanism are in the position of Fig. 1 with the piston rod 52 fully retracted and so held by the engagement of the flat edge of the cutout 74 of stamping 72 in the groove 77 of the piston rod. The switch operator at this time will be in the "on" position as indicated. If the operator had wanted a normal quick-break operation of the switch, he would manually have moved the operator 20 to its "off" 55 position. Wanting a delayed quick-break action, however, he will press in the handle part 80 of the stamping 72 so that the edge of cutout 74 will move out of the groove 77 in piston rod 52 and will release the piston rod. The spring 60 will advance the piston until the button 58 on the end of the piston rod engages the operator 20, after which, further advance of the piston rod will cause the operator 20 to move out of the "on" position, with a quick-break movement, caused by the switch spring. 70 75

5 The speed with which the advance of piston rod 52, and consequently the interval between the time the operator presses in on lug 80, and the time when the mechanism will cause quick-break movement of the operator 20, can be regulated by the screw 65 whose movement provides an adjustable sealing pressure on washer 68 and permits a flow of air into the cylinder 50 thru the threaded opening which receives the threads of screw 65.

10 After the time delay mechanism has actuated the switch, the mechanism may be restored by the operator to its original condition. The operator will force the piston rod 52 back into the cylinder until its groove 77 aligns with the stamping 72 so that the edge of the latter's cutout will engage the piston rod and hold it in place. Return of the piston rod is a comparatively simple manual operation; the user merely places his index finger on the head 66 of screw 65 and his thumb against the bottom of button 58. Squeezing the two together causes the piston rod to return until it is latched by the stamping 72.

15 It will be seen from the foregoing that the accessory is so mounted that it does not interfere with normal operation of the operator 20 and further that the accessory can be mounted with respect to the switch merely by removing one of the screws 26, and thereafter re-inserting it, thru the opening of the mounting plate 40. To mount 20 the accessory, therefore, no electrical connection need be created; no wiring need be affected; no structure need be altered; and no difficulty is encountered.

25 In Fig. 4 there is disclosed in plan view a slightly modified construction which shows a slightly different method of mounting the time delay mechanism. In this figure, the back part 46 and part of the top portion 48 of the stamping 44 are shown, other parts of the time delay mechanism being omitted for the purpose of clarity. The back part 46 is riveted to a mounting plate 90 by a rivet 92 and this mounting plate has its side edges 94 bevelled and hooked over the side edges 96 of the cover plate 24, which cover plate 45 is identical with that of Fig. 1. The connection between the mounting plate and the cover plate may be effected merely by sliding the mounting plate, with the time delay mechanism thereon, over the cover plate, after the cover plate has been 50 removed from its location on the wall 10. When the mounting plate and the mechanism are assembled on a cover plate to form an assembly, the assembly is placed in position on the wall with the screws 26 serving to clasp the assembly 55 in its place.

60 In Fig. 5 a still further modified construction is shown. In this construction the parts 46 and 48 of the stamping 44 are shown as secured to a mounting plate 102 by a rivet 104. The mounting plate has its edges bevelled as at 106 to conform to the bevelled edges 96 of the cover plate 24 and further has countersunk holes 108 aligned with and co-operating with countersunk holes 110 of the cover plate. Screws 26, of which one 65 only is shown, pass thru the holes 108—110 of the plate and secure the mounting plate, not only to the cover plate but with it, to the wall 10. The mounting plate will, of course, be provided with a slot 112 aligned with the slot 28 of the 70 cover plate, to permit the passage therethru of the switch operator 20. In this form also, it is the set of screws 26 which holds the time delay mechanism as a whole in place with respect to the wall 10. 75

In Fig. 6 there is shown a common type of construction, wherein the cover plate 113 has several switch operators or levers 114 projecting thru it. The mounting plate 115 of the accessory is secured thereto by the screws 116 and has a slot 117 in which slides a headed block 118 secured to the back part 46 of the stamping 44, the construction permitting the mechanism as a whole to be moved into registry with any one of the 10 switch operators 114, as desired.

Removal of the mechanism can be effected by sliding the cylinder and its mounting plate completely to the right, so that block 118 will slide out of the open-ended slot 117.

In Fig. 7 there is shown a construction particularly designed for use with a push button switch. In this construction the push buttons 120—122 alternately project forwardly from the wall 124 thru holes in the mounting plate 126, which plate is secured with respect to the wall 124 by the screws 127, one only of which is shown. The time delay mechanism is enclosed within a stamping 128 having a back part 130 riveted at 132 to the plate 126 so as to be rotatable about such rivet to and from the positions shown in the full and dotted lines of Fig. 8, the mechanism being held in place by snap teats 133 being indicated in Fig. 8.

The stamping 128 includes an end part 138 against which the end of the cylinder 136 is spot-welded. Parts 140, 142 and 144, like the correspondingly referenced parts 65, 80 and 58 are also provided. Part 144, which is the operating button of the mechanism, moves to force the push button 122 to the left of Fig. 7 when the time delay mechanism actuates, and this provides a time delay operation to the switch whose "off" operation is controlled by the button 122.

In Fig. 9 there is indicated a construction wherein a time delay mechanism is mounted adjacent a rotary type of switch having a rotary handle or operator 140 projecting forwardly from the surface of the cover plate 24. The time delay mechanism, indicated generally at 154, is shown as mounted on a mounting plate 155 secured in place by screws 26 to which plate is riveted at 156 the stamping 44. The position of the mechanism 154 is such that button 157 thereof will rotate the operator 140 clockwise from the "on" to the "off" position. This figure is provided primarily to indicate that the time delay mechanism may be mounted to co-operate with rotary switches as well as switches of the tumbler and push button type.

In Figures 10-13 there is shown a construction which provides universal adjustment between the accessory mechanism and the switch operator whereby an accessory may be mounted with respect to a switch and adjusted as mounted so as to cooperate with the switch operator regardless of the position of the latter or regardless of variations in manufacture between switches produced by various manufacturers.

For providing vertical adjustment of the accessory with respect to the operator 20, in a direction parallel to the cover plate plane, the mounting plate 40 is provided with an elongated slot 40a through which passes the screw 26 which mounts the accessory on the switch cover plate 24.

For providing adjustment of the accessory with respect to the operator 20 in a direction transverse to the plane of the cover plate 24, the piston rod 52, shown as hexagonal to cooperate with a hexagonal hole in the cover 56 of the cylinder 50

whereby the piston rod is non-rotatable with respect to the cylinder, is provided with a slot 52a on its lower surface for receiving the end of a stamping 53 which is secured to the under surface of the piston rod by means of a screw 55 passing through an elongated slot 57 formed in the stamping, the construction being such that the stamping is non-rotatable with respect to the piston rod, but is movable with respect thereto in a direction transverse to the plane of the cover plate 24, as permitted by the loosening of the screw 55. The stamping is provided with depending wings 59 spaced apart a considerable distance and providing trunnions for journalling a long roller 61 disposed between them, this roller engaging the operator 20 when the piston rod moves downwardly to cause time delay break of the switch. It will be observed that the adjustment of the stamping 53 towards and away from the cover plate 24 compensates for variations in the manufacture of the switches.

It will also be observed that the roller 61 is relatively long; in most cases it is longer than the dimension of the operator 20 in a direction parallel to the plane of the cover plate.

In Figs. 14 and 15 there is shown a construction which provides for automatic operation of the trigger 80. In this construction the cylinder 50 is rotatably mounted on the mounting plate 40, in accordance with the teachings of the foregoing, and the trigger lug 80 is provided on the side of the cylinder rather than in front thereof, as contradistinguished from the construction of Fig. 10 for example. Disposed on the mounting plate 40, adjacent the cylinder 50 when the latter is in its operating position and secured thereto by a screw 83, is a lug 85, the latter projecting from the plane of the mounting plate 40 at least up to the trigger 80, whereby a portion of the lug 85 will be engaged by the trigger lug 81 when the cylinder is swung from the inoperative position shown in dotted lines to the operative position, the trigger lug being pressed in automatically by such engagement without the necessity for the user of the switch pressing in the trigger lug manually in addition to swinging the cylinder down from its horizontal inoperative position to its vertical operating position.

Now having described the invention and various embodiments thereof, reference will be had to the following claims which determine the scope of the invention, it being understood that the invention is not to be considered limited to any specific construction here shown or described.

I therefore claim:

1. The combination of a wall switch having an operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and detachably secured with respect to said plate, by one of the screws which secures the cover plate in place, and thereby secured with respect to said wall, the mounting screw passing through a hole in a projecting and immovable part of the mechanism, the mechanism comprising a cylinder containing a piston, the mechanism mounting projecting part being on the cylinder, the piston normally being constantly influenced out of the cylinder to engage the operator and move it in one direction, the cylinder having means for retarding

the advance of the piston, there being a manually operable latch for restraining the outward movement of the piston.

2. The combination of a wall switch having an operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and detachably secured with respect to said plate, by one of the screws which secures the cover plate in place, and thereby secured with respect to said wall, the mounting screw passing through a hole in a projecting and immovable part of the mechanism, the mechanism comprising a cylinder containing a piston, the mechanism mounting projecting part being on the cylinder, the piston normally being constantly influenced out of the cylinder to engage the operator and move it in one direction, the cylinder having means for retarding the advance of the piston, there being a manually operable latch for restraining the outward movement of the piston, the piston being so formed that its return into the cylinder is free of any operating influence on the switch operator.

3. The combination of a wall switch having an operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and detachably secured with respect to said plate, by one of the screws which secures the cover plate in place, and thereby secured with respect to said wall, the mechanism comprising a cylinder containing a piston, the piston normally being constantly influenced out of the cylinder to engage the operator and move it in one direction, the cylinder having means for retarding the advance of the piston, there being a manually operable latch for restraining the outward movement of the piston.

4. The combination of a wall switch having an operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and detachably secured with respect to said plate, by one of the screws which secures the cover plate in place, and thereby secured with respect to said wall, the mechanism comprising a cylinder containing a piston, the piston normally being constantly influenced out of the cylinder to engage the operator and move it in one direction, the cylinder having means for retarding the advance of the piston, there being a manually operable latch for restraining the outward movement of the piston, the piston being so formed that its return into the cylinder is free of any operating influence on the switch operator.

5. The combination of a wall switch having an operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and

detachably secured with respect to said plate, by one of the screws which secures the cover plate in place, and thereby secured with respect to said wall, the mechanism comprising a cylinder containing a piston, the piston normally being constantly influenced out of the cylinder to engage the operator and move it in one direction, the cylinder having means for retarding the advance of the piston, there being a manually operable latch for restraining the outward movement of the piston, the mechanism being adjustable with respect to the switch whereby the stroke of the piston may be varied.

6. The combination of a wall switch having an operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and detachably secured with respect to said plate, by one of the screws which secures the cover plate in place, and thereby secured with respect to said wall, the mechanism comprising a cylinder containing a piston, the piston normally being constantly influenced out of the cylinder to engage the operator and move it in one direction, the cylinder having means for retarding the advance of the piston, there being a manually operable latch for restraining the outward movement of the piston, the mechanism being adjustably mounted with respect to the switch and adjustably constructed whereby the stroke of the piston may be varied in length and in position.

7. The combination of a wall switch having an operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and detachably secured with respect to said plate, by one of the screws which secures the cover plate in place, and thereby secured with respect to said wall, the mechanism comprising a cylinder and a piston, the piston normally being constantly influenced out of the cylinder to engage the operator and move it in one direction, the cylinder having means for retarding the advance of the piston, there being a manually operable latch for restraining the outward movement of the piston, means providing an adjustable mounting for the cylinder with respect to the cover plate whereby the stroke of the piston may be varied in position.

8. The combination of a wall switch having an operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and detachably secured with respect to said plate, by one of the screws which secures the cover plate in place, and thereby secured with respect to said wall, the mechanism comprising a cylinder and a piston, the piston normally being constantly influenced out of the cylinder to engage the operator and move it in one direction, the cylinder having means for retarding the advance of the piston, there being a manually operable latch for restraining the outward movement of the piston, means providing an adjustable mounting for the

cylinder with respect to the cover plate whereby the stroke of the piston may be varied in position, the piston having a part for engaging the operator, the part being adjustably mounted with respect to the piston whereby the relation of the piston stroke to the operator may be varied.

9. The combination of a wall switch having an operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and detachably secured with respect to said plate, by one of the screws which secures the cover plate in place, and thereby secured with respect to said wall, the mechanism comprising a cylinder and a piston, the piston normally being constantly influenced out of the cylinder to engage the operator and move it in one direction, the cylinder having means for retarding the advance of the piston, there being a manually operable latch for restraining the outward movement of the piston,

10 means providing an adjustable mounting for the cylinder along the cover plate whereby the stroke of the piston may be varied in position, the piston having a part for engaging the operator, the part being adjustably mounted to move towards and

15 from the switch, whereby the relation of the piston stroke to the operator may be varied.

10. The combination of a wall switch having an

operator projecting forwardly from the wall a considerable distance, and concealed by a cover plate in front of and detachably secured with respect to said wall by screws passing therethrough and threaded into a part of the switch, the operator projecting through the cover plate, a time delay mechanism also mounted in front of and detachably secured with respect to said plate, by one of the screws which secures the cover plate in place, and thereby secured with respect to said wall, the mechanism comprising a cylinder and a piston, the piston normally being constantly influenced out of the cylinder to engage the operator and move it in one direction, the cylinder having means for retarding the advance of the piston, there being a manually operable latch for restraining the outward movement of the piston,

10 means providing an adjustable mounting for the cylinder along the cover plate whereby the stroke of the piston may be varied in position, the piston having a part for engaging the operator, the part being adjustably mounted to move towards and from the switch, whereby the relation of the piston stroke to the operator may be varied, the part being of considerable length

15 along the cover plate in a direction transverse to the piston stroke, sufficient to compensate for any irregularities in the position of the mechanism-mounting screw with respect to the operator that might exist.

WILLIAM H. FRANK.
